DESIGN FOR A CASING FOR A TELEPHONE INDEX OR LIKE ARTICLE

Norman Bel Geddes and Worthen Paxton, New York, N. Y., assignors to The Bates Manufacturing Company, West Orange, N. J., a corporation of New Jersey

Application October 21, 1933. Serial No. 49,532

Term of patent 7 years

To all whom it may concern:

Be it known that we, NORMAN BEL GEDDES, a citizen of the United States, and a resident of New York, county of New York, State of New York, and WORTHEN PAXTON, a citizen of the United States, and a resident of New York, county of New York, State of New York, have invented a new, original, and ornamental Design for a Casing for a Telephone Index or Like Article, of which the following is a specification, reference being had to the accompanying drawing, forming a part thereof.

In the drawing:

Figure 1 is a perspective view of a casing for a telephone index or like article showing our new design; and

Fig. 2 is a rear end elevational view of the casing for a telephone index or like article shown in Fig. 1.

We claim:

The ornamental design for a casing for a telephone index or like article, substantially as shown.

NORMAN BEL GEDDES.
WORTHEN PAXTON.
